United States Patent

Des. 241,847
Patented Oct. 12, 1976

241,847

AIR FRESHENER DISPENSER

David A. Jones, Bellbrook, and Lemuel R. Burnet, Jr.,
Cincinnati, Ohio, assignors to The Drackett Company,
Cincinnati, Ohio

Filed May 1, 1975, Ser. No. 573,504

Term of patent 14 years

Int. Cl. D23—04

U.S. Cl. D23—150

FIG. 1 is a perspective view of an air freshener dispenser, showing our new design;

FIG. 2 is a bottom perspective view thereof;

FIG. 3 is a top plan view thereof;

FIG. 4 is a side elevational view thereof; and

FIG. 5 is a bottom plan view thereof.

We claim:

The ornamental design for an air freshener dispenser, as shown and described.
